[57] CLAIM

The ornamental design for a model racing car, as shown and described.

DESCRIPTION

FIG. 1 is a front and side perspective view of a model racing car showing my new design;

FIG. 2 is a left side perspective view thereof, the side opposite being substantially a mirror image;

FIG. 3 is a front perspective view thereof shown on an enlarged scale; and,

FIG. 4 is a rear perspective view thereof.

*Fig. 1**Fig. 2*

*Fig. 3**Fig. 4*
